US0D1099881S

(12) **United States Design Patent** (10) Patent No.: **US D1,099,881 S**
Watrus et al. (45) Date of Patent: ** Oct. 28, 2025

(54) **COMBINED ELECTRONIC DEVICE AND MOUNTING INTERFACE**

(71) Applicant: **SRAM, LLC**, Chicago, IL (US)

(72) Inventors: **Laurence John Watrus**, Santa Monica, CA (US); **Evan Charles Huggins**, Fairfield, IA (US); **Robert David Martinez**, San Francisco, CA (US); **Zakery Allen Koster**, Brooklyn, NY (US); **Paul Thomas Reamey**, Brooklyn, NY (US)

(73) Assignee: **SRAM, LLC**, Chicago, IL (US)

(**) Term: **15 Years**

(21) Appl. No.: **29/786,068**

(22) Filed: **May 28, 2021**

CLAIM

The ornamental design for a combined electronic device and mounting interface, as shown and described.

DESCRIPTION

FIG. 1 a perspective view of a combined electronic device and mounting interface showing our new design;

FIG. 2 is a top view thereof;

FIG. 3 is a bottom view thereof;

FIG. 4 is a right side view thereof;

FIG. 5 is a left side view thereof;

FIG. 6 is a rear view thereof; and,

FIG. 7 is a front view thereof.

Broken lines illustrate portions of the combined electronic device and mounting interface that form no part of the claimed design.

1 Claim, 7 Drawing Sheets
